MILLER REESE HUTCHISON, OF LLEWELYN PARK, NEW JERSEY, ASSIGNEE, BY
MESNE ASSIGNMENTS, TO ACOUSTIC PRODUCTS COMPANY, OF NEW YORK, N. Y., A
CORPORATION OF DELAWARE.

LOUD-SPEAKER UNIT.

Application filed February 26, 1927. Serial No. 171,350.

- This invention relates to telephone devices of the loud speaking type and has for its principal object the amplification and reinforcement of compressional wave energy.
- 5 A feature of the invention relates to the provision of a tuned telephone receiver diaphragm having adjacent thereto a resonating column of compressible fluid for reinforcing compressional waves of predetermined frequency.
- 10 A further object of the invention relates to the combination with a tube of restricted diameter having a flare joining the tube to a casing of relatively greater diameter of a tuned diaphragm forming an end wall of the casing and in contact with the compressible fluid defined by the flared tube. According to this feature the fluid within the tube resonates to a predetermined natural frequency in consonance with the tuned diaphragm so as to produce greatly amplified effects when the device is actuated at the predetermined frequency.
- 15 Another feature of the invention relates to the provision of a stationary electromagnet having aligned solenoids with converging pole pieces with a metallic element positioned at the convergence of the pole pieces and a vibratory element joined to the metallic element by means of a link or rod extending between the pole pieces.
- 20 Other objects will appear from the following description and claims taken in connection with the accompanying drawing in which there is shown a side elevation, partly in section, of a structure embodying features of the invention.
- 25 In the following description and claims, parts, characteristic features and functions will be identified by specific names for convenience of expression, but they are intended to be as generic in their application to similar or equivalent construction as the art will permit.
- 30 Referring to the drawing, there is shown a tube of restricted diameter throughout the main portion of its length and terminating at one end in an enlarged bell 11. At the opposite end the tube 10 is provided with a flare 12 to the periphery of which there is secured an open ended cylindrical casing 13 having a diameter to conform to the greatest diameter of the flare 12. The casing 13 includes an outer peripheral wall 14, serving as a protective covering. Within the wall 14 and adjacent to the flare 12 there is provided an annular washer 15 formed preferably of cork. A relatively thin metal diaphragm 16 is seated on the cork washer 15 and is clamped in place thereon by a second washer 17, also preferably formed of cork. The material of which the washers 15 and 17 are formed is of such nature that after being compressed to substantially one-eighth of its original thickness, it returns to one-half of that original when the pressure is removed, but retains a remarkable resiliency even under adverse conditions. The washers 15 and 17 are understood to have been so treated and thus serve very efficiently as clamping members for the diaphragm. The washers are maintained in fixed position for so clamping the diaphragm 16 in place by an inner peripheral wall 18 secured to the outer wall 14 and thus forming a part of the casing 13. The walls 14 and 18 are formed of a magnetically inert material such as brass. The diaphragm 16 may be tuned to a predetermined frequency as will appear hereinafter.
- 35 Secured to the inner wall 18 and extending radially inwardly therefrom are spaced magnet cores 20, 20, shown two in number formed of laminations of para-magnetic material, the inner end portions thereof being bent into partial convergence. The greater portion of each core is substantially straight, and is in alignment with the similar portion of the other core.
- 40 Near the convergence of the magnet cores 20, 20, there is provided a movable armature 21 formed of para-magnetic material and operatively connected by a link 22 to the middle portion of the diaphragm 16. The normal adjustment is such that the armature 21 is spaced apart from the ends of the cores 20, 20.
- 45 For permanently magnetizing the cores 20, 20, there is provided a plurality of permanent

- magnets shown 3 in number as at 30, 31, 32. These may preferably take the form of arcuate concentric elements permanently magnetized and having an intimate magnetic contact with the cores 20, 20 thus serving to produce a magnetic field of force extending from one pole 20 by way of the armature 21 to the other pole. For modifying this magnetic field of force in accordance with a signal, 10 there is provided on one of the cores 20, a magnet coil 33 and a similar magnet coil 34, provided on the other magnet core. The electro-magnets 33, 34 are connected in circuit with a source of undulatory energy of audio 15 frequency such as a radio receiving set, a public audio system or a power amplifier, but as such source forms no part of the present invention it is thought that a further description thereof is not required.
- 20 The upper end of the casing 13 may be provided with a wall 40 which may be in the form of a sheet of gauze, or there may be provided a tuned chamber or resonator tuned to resonate at the same frequency, to which the 25 horn 1, 2 is tuned.
- In operation undulatory current of speech frequency is applied to the magnets 33, 34 and modifies the pull of the magnetic field upon the armature 21, thus causing movement 30 of the armature in accordance with the signal current impressed upon the magnets. This movement is communicated by the link 22 to the diaphragm 16 and thus produces compressional waves in the compressible medium 35 defined by the tube 10. When the energy impressed upon the magnets 33, 34, of the frequency to which the fluid within the tube 10 resonates, greatly amplified sounds are emitted from the device.
- 40 Thus it will be seen that I have provided a device for producing compressional waves of greatly amplified intensity.

What is claimed is:—

1. In a telephone device, the combination 45 of stationary electromagnets having aligned cores, the end portions thereof being bent into partial convergence, a movable armature positioned adjacent the ends of said cores on one side of the magnet, a diaphragm on the 50 opposite side of the magnet and operatively connected to the armature, and a resonant chamber adjacent said diaphragm for emphasizing the action of the diaphragm with respect to predetermined notes of the musical 55 register.
2. In a telephone device, the combination 60 of stationary electromagnets having aligned cores, the end portions thereof being bent into partial convergence, a movable armature positioned adjacent the ends of said cores on one side of the magnet, a diaphragm on the 65 opposite side of the magnet and operatively connected to the armature, and tuned to a predetermined natural frequency, and a resonant chamber adjacent said diaphragm for 70

emphasizing the action of the diaphragm with respect to notes having said predetermined frequency.

3. In a sound producer, a cylindrical casing, an electromagnet within said casing, an 75 armature actuated by said magnet, a diaphragm tuned to a predetermined frequency and forming an end wall of said casing, a tube having a restricted diameter and joined to the casing by a flare, said tube defining 80 an air column adjacent the diaphragm and tuned to re-enforce the action of the diaphragm.

4. In a loud speaker, a flared tube defining 85 a column of compressible fluid resonant to a predetermined natural frequency, a vibratory element positioned on the flare of said tube and having one surface in contact with the fluid within said tube, an electromagnet proximate a different surface of said element, a movable armature controlled by said magnet, and a link operatively interconnecting the armature and the vibratory element.

5. In a loud speaker, a flared tube defining 90 a column of compressible fluid resonant to a predetermined natural frequency, a vibratory element positioned on the flare of said tube and having one surface in contact with the fluid within said tube, an electromagnet proximate a different surface of said element, 95 said magnet having a pair of spaced pole pieces, a movable armature controlled by said magnet, and a link extending between said pole pieces and operatively interconnecting the armature and the vibratory element.

6. In a loud speaker, a flared tube defining 100 a column of compressible fluid resonant to a predetermined natural frequency, a vibratory element positioned on the flare of said tube and having one surface in contact with the fluid within said tube, said element having a natural frequency having a predetermined relation to the natural frequency of the resonant fluid column, an electromagnet proximate a different surface of said element, a 105 movable armature controlled by said magnet, and a link operatively interconnecting the armature and the vibratory element.

7. In a loud speaker, a flared tube defining 110 a column of compressible fluid resonant to a predetermined natural frequency, a vibratory element positioned on the flare of said tube and having one surface in contact with the fluid within said tube, said element being tuned into consonance with the musical note 115 to which the fluid column resonates, an electromagnet proximate a different surface of said element, said magnet having a pair of spaced pole pieces, a movable armature controlled by said magnet, and a link operatively interconnecting the armature and the vibratory element.

8. A sound producer comprising in combination a relatively confined column of atmospheric medium resonant to a predetermined 120

natural frequency, a diaphragm adjacent said column, and means for actuating said diaphragm comprising a pair of alined electromagnets having converging pole pieces.

5 9. A sound producer comprising in combination a resonant air column, a diaphragm adjacent said air column, and means for actuating said diaphragm comprising a pair of

alined electromagnets, pole pieces of which are surrounded by permanent magnets and electromagnets.

Signed at New York, in the county of New York and State of New York, this 24th day of February, A. D. 1927.

MILLER REESE HUTCHISON.
